UNITED STATES PATENT OFFICE.

EDWARD GERMAIN, OF SAGINAW, MICHIGAN.

DESIGN FOR A MANTEL.

SPECIFICATION forming part of Design No. 21,157, dated November 10, 1891.

Application filed October 14, 1891. Serial No. 408,725. Term of patent 7 years.

To all whom it may concern:

Be it known that I, EDWARD GERMAIN, of Saginaw, in the State of Michigan, have invented and produced a new and original Design for Mantels, of which the following is a specification.

In the accompanying drawings, Figure 1 is a front elevation of the mantel. Fig. 2 is a transverse sectional elevation of the same to show more clearly the outline and configuration of the parts.

a are the pilasters. b are the plinths; c, the caps; d, the frieze; e, the mantel-board; f, the grounds, and g the fire-strips. Each pilaster is formed with plain beveled edges h and with two longitudinal grooves i conterminous with the bevels. The plinths are thicker and wider than the pilasters, projecting beyond the pilasters both in front and on the sides. On the upper portion of the face of each plinth is a molding, which, as seen more clearly in the side elevation, Fig. 2, consists of an upper level b', a lower bevel b², and an intermediate ogee-shaped surface b³. The caps have sunken or intagliated rosettes j, and are provided or formed with beveled lower and side edges k of the shape shown. These bevels are not plane, but concave in cross-section. The frieze has a straight plain lower edge, be-

neath which is a molding l. Upon the frieze is a raised panel m, which terminates short of the ends of the frieze and has parallel sides and rounded convex ends, the edges of both the ends and sides of the panel being beveled, the bevel, as seen at n, being continuous all around the panel and being concave to match the concave bevel on the edges of the caps. It is in this paneled frieze, in conjunction with the pilasters and plinths of the configuration above described, and the caps c that the characteristic feature of the design is found.

o is the filling-strip at the upper part of the frieze, having a beveled lower edge o'. p is a molding beneath the mantel-board.

The fire-strips g and the side strips of the grounds f are molded, as shown.

What I claim, and desire to secure by Letters Patent, is—

The design for a mantel, as herein described and shown.

In testimony whereof I affix my signature in presence of two witnesses.

EDWARD GERMAIN.
